Term of patent 14 years

(Cl. D34—15)

Fig. 1.

Fig. 2.

To all whom it may concern:

Be it known that I, Bert L. Murman, a citizen of the United States, residing at Los Angeles, in the county of Los Angeles and State of California, have invented a new, original, and ornamental Design for a Toy Tender or Similar Article, of which the following is a specification, reference being had to the accompanying drawing forming part thereof.

Fig. 1 is a perspective view of a toy tender or similar article showing my new design; and

Fig. 2 is a side elevational view thereof.

A portion of the tethering cord has been broken away in the drawing figures for convenience of illustration.

I claim:

The ornamental design for a toy tender or similar article, substantially as shown and described.
